DESCRIPTION

U.S. PATENT DOCUMENTS

FIG. 1 is a front perspective view of a musical instrument slide with collar embodying the design;

FIG. 2 is a left side elevational view thereof;

FIG. 3 is a rear elevational view thereof;

FIG. 4 is a right side elevational view thereof;

FIG. 5 is a bottom plan view thereof;

FIG. 6 is a top plan view thereof; and,

FIG. 7 is a sectional view along line 7-7 of FIG. 3; the broken lines indicate the presence of liquid within the musical instrument slide with collar.
